UNITED STATES PATENT OFFICE.

ROBERT GILMOUR AND ERNEST E. COOK, OF PAWTUCKET, RHODE ISLAND.

GAS-PRESSURE REGULATOR.

Application filed March 30, 1922. Serial No. 548,252.

To all whom it may concern:

Be it known that we, ROBERT GILMOUR and ERNEST E. Cook, citizens of the United States of America, residing at Pawtucket, in the county of Providence and State of Rhode Island, have invented certain new and useful Improvements in Gas-Pressure Regulators, of which the following is a specification.

10 This invention relates to certain new and useful improvements in gas regulators, particularly intended to equalize the pressure of gas in house mains and pipes.

Objects of the invention are to generally 15 simplify and improve devices of the above kind and to provide a device of such type capable of being cheaply and easily manufactured from standard pipe fittings or the main portions of its construction, thereby 20 providing a way for quantity production so as to meet with the requirements for a successful commercial use and to present a device which will have the appearance of the ordinary pipe line slightly enlarged, 25 when in use.

Another object of the invention is to minimize the number of movable parts to such an extent that very little chance of the device of getting out of order is had, and 30 wherein the movable parts are of such a nature as to not become worn or inoperative during continued use.

With the above and general objects and others that will appear as the nature of the 35 invention is better understood, the same consists in the novel construction, combination and arrangement of parts hereinafter more fully described, illustrated in the accompanying drawings, and pointed out in 40 the appended claims.

In the drawings:

Figure 1 is a view partly in substantially central longitudinal section and partly in side elevation of a gas regulator constructed 45 in accordance with the present invention and shown operatively connected to supply an outlet pipe, fragments of which are shown respectively in side elevation and in longitudinal sections.

50 Figure 2 is a horizontal sectional view taken on line 2—2 of Figure 1 and

Figure 3 is a side elevational view of the inverted gas controlling cup with its attached handle or stem.

55 Referring more in detail to the several views, the present invention embodies a

casing constructed of a main body portion formed of a length of relatively large pipes as indicated at 5 which is externally threaded at its ends, and a pair of bushings 6 of the same diameter, one at each end of the body member 5 and having their end edges in contiguous abutting relation as shown, the bushings 6 being similarly externally threaded. Coupling sleeves 7 of the internally threaded type are threaded onto the adjacent portions of the bushings 6 and the body member 5 so that each coupling sleeve connects one bushing detachably to the body member 5 with a substantially gas tight joint. Obviously, this joint may be additionally rendered gas tight by the use of any suitable form of packing between the abutting ends of the body member 5 and the bushings 6 or by providing a leaded joint as is usually practiced in the plumbing art with respect to screw threaded connections. By thus coupling the bushings 6 to the ends of the pipe section 5 a hollow elongated casing is thus formed from 80 commercial fitting capable of being assembled cheaply and easily as well as expeditiously and presenting in appearance substantially nothing more than coupled pipe fittings.

The opening in the end of the upper bushing 6 is internally threaded for the reception of an end of an outlet pipe 8 which is connected to various burners or the like where the gas is consumed, and the lower bushing 6 is similarly provided with an internally threaded opening in which is screwed an inlet pipe 9 of such length as to project a considerable distance upwardly into the casing, the diameter of the pipe 9 being somewhat smaller than the diameter of the pipe section 5 of the casing so as to leave an annular space between these members as shown in which is poured an anti-freezing compound or liquid 10 which 100 may consist of equal parts of water and glycerine.

The lower end of the inlet pipe 9 has one branch of a tee fitting 11 threaded thereon and the opposed branch of the same has a removable plug 12 while the intermediate part of the tee fitting 11 communicates with a gas supply pipe 13. The sediment may be removed from the pipe 9 and fitting 11 from time to time by removal of the plug 12.

Loosely disposed within the casing is an inverted cup shaped gas controlling bell or

member 14 whose upper wall is adapted to normally rest upon the upper end of the inlet pipe 9, the barrel including a cylindrical wall of slightly greater diameter than that of the pipe 9 and of slightly lesser diameter than that of the pipe section 5 of the casing. Thus, an annular space is provided between the cylindrical wall of the inverted cup member 14 and each of the pipes 9 and 5 and 5 the cylindrical wall of the member 14 surrounds the upper end of the pipe 9 as shown. The lower portion of the cylindrical wall of the inverted cup shaped gas controlling member 14 is provided with a plurality of 10 horizontal series of perforations or openings 15, one circular series being provided in a horizontal plan above another as clearly illustrated in Figures 1 and 3 and the liquid 10 being placed in the casing to such a depth 20 as to fill said casing to a point slightly above the highest row of openings 15 when the cup member rests upon the upper end of the inlet pipe 9. The bottom of the inverted cup shaped member 14 may be provided with an 25 axial upwardly extending stem 16 adapted to form a handle which may be grasped for removing the member 14 after the upper bushing has been uncoupled from the casing section 5 in case renewal or repair of this 30 member 14 is ever found necessary.

As the demand for gas, by the lighting and opening of new burners in a house, increases, it will lessen the pressure on the top or above the gas controlling cup member 14 35 by the withdrawal from the casing of a quantity of the gas which fills said casing. As a result, the member 14 will rise slightly, thus exposing one or more of the rows or orifices or openings 15 of the cup, and thus 40 permitting the escape of more gas from the inlet pipe 9. When the burners are shut off, the reverse takes place. It will be seen that the cup is so arranged and is of such a construction that it will be supported or will 45 float partly on the liquid contained in the cylinder and partly on account of the pressure of the gas beneath it, the general principle being the flow into the cylinder or casing from the main will be increased and this 50 cup rises and decreases as the cup falls or lowers.

While the form of the invention herein shown and described is what is believed to be the preferred embodiment thereof, it is nevertheless to be understood that various forms, modifications and arrangements of the parts may be made without departing from the spirit and scope of the invention as claimed.

60 What we claim is new is:—

1. A gas regulator of the type described comprising an elongated hollow casing having an axial relatively smaller outlet pipe at one end and a similar inlet pipe at the other 65 end, said inlet pipe projecting into the cas-

ing axially of the latter for a distance, an inverted cup shaped member loosely fitted in the casing with its side walls in spaced relation to and surrounding the inwardly projecting end of the inlet pipe and including 70 an upper wall member normally adapted to rest upon the upper end of the inlet pipe within the casing, said side walls of the inverted cup shaped member being provided with a series of horizontal rows of perforations and the upper wall of the same being imperforate and said casing having a body of liquid therein of a depth to extend above the highest row of perforations in the inverted cup member when the latter is normally positioned, said casing comprising a pipe section externally threaded at each end, bushings of similar diameter each having an end edge abutting an end edge of the pipe section and being externally threaded, and internally threaded coupling sleeves connecting the bushing to the pipe section with the joints between the bushings and the pipe sections air tight, said inlet and outlet pipes being threaded centrally through the bushings. 75 80 85 90 95

2. A gas regulator of the type described comprising an elongated hollow casing having an axial relatively smaller outlet pipe at one end and a similar inlet pipe at the other end, said inlet pipe projecting into the casing axially of the latter for a distance, an inverted cup shaped member loosely fitted in the casing with its side walls in spaced relation to and surrounding the inwardly projecting end of the inlet pipe and including 100 an upper wall member normally adapted to rest upon the upper end of the inlet pipe within the casing, said side walls of the inverted cup shaped member being provided with a series of horizontal rows of perforations and the upper wall of the same being imperforate and said casing having a body of liquid therein of a depth to extend above the highest row of perforations in the inverted cup member when the latter is normally positioned, said casing comprising a pipe section externally threaded at each end, and bushings of similar diameter each having an end edge abutting an end edge of the pipe section and being externally threaded, internally threaded coupling sleeves connecting the bushings to the pipe section with the joints between the bushings and the pipe sections air tight, said inlet and outlet pipes being threaded centrally through the bushings, a tee fitting having a branch threaded on the lower end of the inlet pipe outwardly of the casing and having its opposed branch provided with a removable cleaner plug, and a supply pipe connected with the remaining corner of said tee fitting. 105 110 115 120 125 130

having an axial relatively smaller outlet pipe at one end and a similar inlet pipe at the other end, said inlet pipe projecting into the casing axially of the latter for a distance, an inverted cup shaped member loosely fitting in the casing with its side walls in spaced relation to and surrounding the inwardly projecting end of the inlet pipe and including an upper wall member normally adapted to rest upon the upper end of the inlet pipe within the casing, said side walls of the inverted cup shaped member being provided with a series of horizontal rows of perforations and the upper wall of the same being imperforate and said casing having a body of liquid therein of a depth to extend above the highest row of perforations in the inverted cup member when the latter is normally positioned, said casing comprising a pipe section externally threaded at each end, and bushings of similar diameter each having an end edge abutting an end edge of the pipe section and being externally threaded, internally threaded coupling sleeves connecting the bushings to the pipe section with the joints between the bushings and the pipe section air tight, said inlet and outlet pipes being threaded centrally through the bushing, a tee fitting having a branch threaded on the lower end of the inlet pipe outwardly of the casing and having its opposed branch provided with a removable cleaner plug, and a supply pipe connected with the remaining corner of said tee fitting, said inverted cup member having an axial upwardly projecting stem adapted to form a handle therefor.
